[57] CLAIM

The ornamental design for a vehicle luggage rack, as shown and described.

DESCRIPTION

FIG. 1 is a perspective view of a vehicle luggage rack, showing our new design;

FIG. 2 is a top plan view thereof;

FIG. 3 is a left side elevational view thereof, the right side being a mirror image;

FIG. 4 is an enlarged rear elevational view thereof, the front being a mirror image.

The vehicle shown in broken lines in the figures is shown for illustrative purposes only and forms no part of the claimed design.

FIG. 1

FIG. 2
